UNITED STATES PATENT OFFICE

PHILIP L. O'DONNELL, OF NORWOOD, OHIO, ASSIGNOR TO PARCO SPECIALTY CO., OF LYNN, MASSACHUSETTS, A CORPORATION OF MASSACHUSETTS

BINDING TAPE

Application filed July 5, 1929. Serial No. 376,027.

This invention relates to an improved edge binding tape such as is used for trimming the exposed edges of shoe uppers and has for an object the provision of a tape which may be 5 stitched to an upper without difficulty and which may subsequently be folded about the edge of the upper and adhesively attached thereto.

Another object is to provide a novel process 10 of preparing binding tape so as to render it thoroughly effective and especially applicable to silk binding tapes such as are used for high grade shoes.

These and other objects are attained by the 15 means and method described herein and illustrated in the accompanying drawing in which:

Fig. 1 is a perspective view of a prepared section of material from which the tape of 20 the invention is formed.

Fig. 2 shows a similar section divided to form two lengths of binding tape.

Fig. 3 is a cross sectional view of a fragment of a sewing machine attaching the tape 25 of the invention to a piece of material to be bound or edged with the tape.

In the binding of the edges of shoe uppers I have found that binding tape having a 30 selvaged edge and one cut or non-selvaged edge most effective, both because the stitching is more secure and because the resultant bead or edging is stronger and more attractive.

To prepare the tape of my invention I employ a double selvaged tape 5 having selvages 35 6 along opposite longitudinal edges. In order to render the drawing clearly readable the various dimensions of parts have been exaggerated. In actuality the faces of the body of tape 5 lie in planes several thousandths of an 40 inch lower than the highest portions of the selvage 6 on adjacent sides so that the entire tape has a relatively broad and very shallow channel 7 extending longitudinally along each face. One of these channels is filled with heat 45 plastic adhesive 8 which also impregnates or

coats the body 5 of the tape but does not discolor the opposite face of the tape. The adhesive 8 is applied sufficiently heavy so that it does not extend above the top of the selvage 6. When using silk tape as purchased in the open market it has been found that the adhesive 8 may be about three one-thousandths of an inch thick with excellent results. The material thus prepared is allowed to become cool so that the adhesive substance is no longer tacky whereupon the tape is divided longitudinally through the impregnated portion to form two binding tapes such as shown in Fig. 2. The binding tape is then ready to be wound on reels or bobbins for use. The tape 60 is sewed through the selvage 6 to the face 9 of a shoe upper or the like adjacent the edge 10 of said upper. The tape guide 11 of the sewing machine is concave and the untreated face of the binding tape rides over the guide 65 without any tendency to adhesion. The selvage 6 is disposed somewhat diagonally of the path of the needle so that the needle will stitch through the untreated selvage so far as can be determined. At any rate the needle does 70 run smoothly as through untreated tape so long as an excessive amount of adhesive has not been deposited in the channel 7 of the tape. It is difficult to determine whether the needle does or does not pierce some of the impregnated or coated portion of the tape but it is true that when the adhesive is about 75 three one-thousandths of an inch thick no difficulty is experienced in stitching the treated tape to the upper in the manner shown and 80 explained.

As a precaution against any possible difficulty in stitching the tape by machine because of possibly excessive adhesive, or excessively hot climate conditions, the tape, 85 after impregnation, as explained may have a minutely thin treatment of wax as shown (in exaggerated proportion) at 13 applied at the time of manufacture. This waxing is not applied over the entire adhesive but only 90

over a very narrow edge margin scarcely wider than the selvage. The waxing 13 comprises a mere rubbing of wax rather than an applied layer or appreciable thickness of wax. The purpose of this waxing is to lubricate the needle and thread during the stitching operation. When the tape is thus treated less exacting manufacturing methods may be pursued and all climatic and shop temperature conditions are met. The tape is in all practical respects to be considered full adhesive coated. The waxing produces the effect of a part coated tape in so far as the stitching operation is concerned but produces better results in the adhesive binding upon the material.

The tape is stitched to the material without difficulty and when the binding is ready to be turned about the edge of the material in the manner well known to those versed in the art, the tape is heated slightly in advance of the operation of the folding machine thereon so that even the most delicately colored or white silk edge binding will not become soiled, nor will the adhesive soil the material to which the edging is applied.

The foregoing disclosure of the tape and method of making and applying it is not to be considered as limited to the exact figures given since they may be varied with different materials used.

What is claimed is:

1. An article of manufacture comprising a binding tape having a beaded selvage, a coating of heat plastic adhesive on one face of the tape, and a narrow coating of a non-fluid lubricating material superposed on a portion of the adhesive adjacent to said beaded edge whereby a sewing needle may penetrate without adhesion to said adhesive.

2. An article of manufacture comprising a binding tape having a beaded selvage, a coating of heat plastic adhesive on one face of the tape, the surface of said coating lying in a plane between that of the face of the tape and the top of the beaded edge, a narrow coating of lubricating wax superposed on a portion of said adhesive adjacent to the beaded edge whereby a sewing needle may penetrate without adhesion to said adhesive.

3. An article of manufacture comprising a binding tape having a beaded selvage, a coating of heat plastic adhesive on one face of the tape and of such thickness as to extend slightly below the top of the beaded edge, a narrow coating of lubricating wax superposed on the coating of adhesive adjacent the beaded edge and of a thickness substantially equal to the difference between the height of the bead above the surface of the tape and the thickness of the coating of adhesive.

4. An article of manufacture comprising a binding tape having beaded selvages along opposite longitudinal edges, a coating of heat

plastic adhesive on one face of the tape intermediate the beaded selvages, the surface of said coating lying in a plane between the plane of the face of the tape and the plane defined by the beaded selvages, and a narrow 70 coating of lubricating wax superposed on each of the margins of said adhesive coating adjacent to the beaded selvage.

In testimony whereof, I have hereunto subscribed my name this 25 day of June, 1929.

PHILIP L. O'DONNELL.
